DESIGN FOR A NASAL INHALER

Harold F. Temple, Freeport, Long Island, N. Y.

Application January 4, 1938, Serial No. 74,077

Term of patent 3½ years

To all whom it may concern:

Be it known that I, Harold F. Temple, a citizen of the United States and resident of Freeport, Long Island, in the county of Nassau, State of New York, have invented a new, original, and ornamental Design for a Nasal Inhaler, of which the following is a specification, reference being had to the accompanying drawing, forming part thereof.

Fig. 1 is a side elevational view of a nasal inhaler showing my new design.

Fig. 2 is a front elevational view of the same.

Fig. 3 is a horizontal sectional view taken on the line 3—3 of Fig. 1.

Fig. 4 is a rear elevational view thereof.

The characteristic features of my design reside in the nasal inhaler as shown, having longitudinal ribs of substantially triangular cross-section on the outer cylindrical surface thereof, said ribs being spaced apart a distance greater than their greatest width, with the upper and lower ends thereof bevelled to a different extent.

I claim:

The ornamental design for a nasal inhaler substantially as shown and described.

HAROLD F. TEMPLE.
